UNITED STATES PATENT OFFICE.

ARTHUR E. JOHNSTONE, OF NEW YORK, N. Y.

FLASH-LIGHT APPARATUS.

SPECIFICATION forming part of Letters Patent No. 603,332, dated May 3, 1898.

Application filed December 29, 1896. Serial No. 617,420. (No model.)

To all whom it may concern:

Be it known that I, ARTHUR E. JOHNSTONE, a subject of the Queen of Great Britain, and a resident of New York city, in the county of 5 New York and State of New York, have invented certain new and useful Improvements in Flash-Light Apparatus, of which the following is a specification.

This invention relates to means for igniting 10 combustible compounds, particularly such as are commonly employed in "flash-light photography."

The main object of the invention is to ignite 15 such compounds from underneath, thus avoiding some of the objections hitherto obtaining to the use of the "flash-light." Thus it is desirable that the igniters should remain clean and hot and that the igniters should not be oxidized. Inasmuch as the igniters 20 are commonly made of platinum, which oxidizes in the presence of carbon, considerable annoyance and difficulty from this source have been experienced with those forms of apparatus in which the needles or igniters 25 strike from above, as the igniters are then in the flashing mixture.

Another object is to keep the apparatus free from ash or smut formed by the combustion of the flash-light compound. With the 30 igniters striking from above it is practically impossible to keep the apparatus, particularly the igniters and their carriers, sufficiently free from smut or ashes and oxidation to have a reliable apparatus. Any ashes or 35 smut or oxidation on the igniters impairs their efficiency as conveyers of heat to the compound to be flashed.

Other objects will hereinafter appear more at large.

To these ends the invention includes the 40 combination of a foraminous holder for the ignitable compound, a source of heat, one or more upwardly-striking igniters, and mechanism for moving the igniter (or igniters) to 45 and fro between said source of heat and said compound.

The invention also includes the combination 50 of a trough-like holder for the ignitable compound, one or more perforations in the bottom of said holder, one or more upwardly-striking igniters, a source of heat, and mech-

anism for moving said igniter (or igniters) to and fro between said source of heat and said perforation to the compound; and the invention also includes other combinations, as will 55 hereinafter be more fully pointed out.

The preferred form of the invention is illustrated in the accompanying drawings, forming part hereof, in which—

Figure 1 is a plan view of the apparatus. 60 Fig. 2 is a vertical sectional view on the plane indicated in Fig. 1 by the line 2 2. Fig. 3 is a similar view upon the plane indicated in Fig. 1 by the line 3 3. Fig. 4 is a vertical longitudinal view of one end of the holder 65 upon the plane indicated in Fig. 1 by the lines 4 4.

In the drawings the reference-numeral 3 indicates an open-ended trough for holding the ignitable compound.

The numeral 4 indicates clips pivoted inside the trough 3 to the sides thereof, as at 5. The said clips are pressed upwardly at their outer ends by suitable springs, as flat or leaf springs 6, which are secured to the bottom of 75 the trough 3 at one end. The bottom of the trough 3 is provided with a slot or series of holes 7, the said slot or holes passing through the bottom, as shown, and being disposed along the longitudinal center of the holder or 80 trough, as shown.

In the use of the apparatus thus far described I place a sheet of paper or fabric 8 in the trough, holding it down by the clips 4, and put the ignitable compound, as powder 9, on 85 the paper or fabric. I prefer to have this paper or fabric 8 of a fireproof nature, since it may then be used over and over to protect the holder 3 from the ash or smut made by the combustion of the ignitable compound. 90 The paper or fabric 8 may be removed at any time from the trough, carrying with it the ash or smut, and be replaced by a fresh one.

For the purpose of igniting the compound from the bottom I employ movable igniters 10, 95 which are normally held in a suitable flame or other heater and are projected through the slot or perforations 7 in the bottom of the holder, where they pierce the paper or fabric 8 and pass into the ignitable compound, as 100 powder 9, and ignite the same. I prefer to have a series of these igniters 10 and to place

them upon the pivoted arms 11. These arms 11 have a common axis of motion, as the shaft 12, which is journaled in lugs 13, which project from the trough 3, or the shaft may be 5 centered at its extremities, as will be readily understood. The arms 11 are preferably provided with enlargements or heads 14 at their free extremities for the purpose of storing heat to keep the needle-like igniters 10 sufficiently hot. The needles or igniters 10 may be integral with these heads; but I prefer to have the igniters of some neutral metal, as platinum, and attach them to the said heads in any suitable way. The shaft 12 is provided 15 with a pin or stop 16, which is carried by a collar 17, loose upon and adjustably fixed to the shaft 12 by the set-screw 18, which passes through the collar 17 and bears against the shaft. This stop 16 coacts with one of the 20 lugs 13 to limit the throw of the shaft in one direction. A spring 15, which is loosely coiled about shaft 12, has one end caught under one of the lugs 13 and the other end under one of the arms 11 and serves to hold the stop 16 against the corresponding lug 13. The arms 25 11 may be adjustably or otherwise attached to the shaft 12. Any suitable mechanism may be employed to rock the shaft 12 for the purpose of throwing the needles or igniters 10 from the flame 2 through the perforations 7 to ignite the composition, as powder 9. (See the dotted lines in Fig. 3.) The preferred means of so moving the igniters is illustrated in Figs. 1 and 2, in which a cylinder 19, open 30 at one end and closed at the other, is fixed to a lug or ear 20 of the trough 3, preferably at the center thereof. Within the cylinder 19 is a piston 21, which is connected with the shaft 12, above named, by means of the piston-rod 22, a flexible wire, cord, or chain 23, fast to the rod 22, and a pulley 24 on the shaft 12, to which pulley the ligament 23 is made fast, as at 25. The piston-rod 22 is fast to the piston 21 and passes through a hole in 35 the closed end of the cylinder 19. A pipe 26 is screwed into a perforation in the end of the fixed cylinder 19. The reference 27 indicates a rubber tube connecting the pipe 26 with a hollow rubber hand-bulb, such as commonly 40 employed by photographers for operating the air-engine of the shutter apparatus of the camera. The spring 15, shaft 12, pulley 24, ligament 23, rod 22, and piston 21 are so disposed relatively to each other that when the 45 piston 21 is forced to the right in Fig. 2 the shaft 12 is rotated against the force of spring 15, and the igniters 10 are thrown from the positions indicated in full lines in Figs. 1, 2, and 3 to the position indicated in dotted lines 50 in the last-named figure, and the ignitable composition 9 is flashed. In order to prevent undue noise and shock, I prefer to place a strip of sound-deadening material 28 on the under side of the trough 3 in such position 55 that the weights 14 will strike against the same, as indicated in Fig. 3. The said sound-deadening material is provided with perfora-

tions which register with the perforations 7 hereinbefore named. I also prefer to employ a buffer which shall come into action 70 just previous to the time that the heads 14 strike the sound-deadener 28. This buffer is conveniently made in the form of a flat or leaf spring 29, which is rigid with and carried by a sleeve 30, adjustably attached to 75 one end of the shaft 12, as by set-screw 31. The air-engine shown in the drawings and hereinbefore described is preferably operated from the same hollow rubber hand-bulb employed for operating the air-engine of the 80 shutter of the camera, and in order that the shutter may be opened before the light is flashed I make the cylinder of the air-engine of the flash-light apparatus of larger internal diameter than the like diameter of the air-engine of the shutter. I also make the tubes 85 26 27 of smaller internal diameter than the like diameter of the tube connecting the air-bulb with the air-engine of the shutter. It follows from this construction that the shutter is opened before the powder 9 is ignited 90 by the needles 10.

The numeral 2 marks a projection on the under side of the trough 3, which screws upon a standard 1. This standard is provided with 95 a shelf for carrying the spirit-lamp or other means employed for heating the igniters 10 and is preferably adjustable in a vertical direction relatively to a tripod or the like commonly employed in photographic galleries for 100 the head-rests for sitters, as will be readily understood.

The collar 24 above named is preferably attached to the shaft 12 in an adjustable manner, as by the set-screw 32. This adjustable connection of the collar with the shaft permits of the taking up of any stretching of the ligament 23.

It will be observed that the throw of the igniters 10 is more than ninety degrees. This 110 great throw is permitted by the nature of the mechanism shown for projecting or throwing the said igniters. It is advantageous to get the source of heat as far from the ignitable compound as possible, and this is permitted by the aforesaid mechanism.

While the apparatus shown in the drawings is intended for use in a horizontal position, it is also capable of use in other positions, as the vertical.

I remark that an advantage in having the igniters strike upwardly is that they have a quicker returning action and that they are less liable to catch in or become entangled with clothing, draperies, &c., than where they 125 are arranged above the composition-holder.

Instead of having the paper or fabric 8 of a fireproof nature it is obvious that the same may be of an inflammable nature and so furnish the flash-light or ignitable compound, 130 thus dispensing with the powder or other compound 9, indicated in the drawings.

The holder, instead of being of a solid form of metal, may be formed of paper or fabric,

preferably fireproof, stretched on a frame, and the igniters perforate it to reach the compound.

The invention is capable of being embodied in many forms. Hence I do not limit myself to the form thereof shown in the drawings and above described.

What is claimed is—

1. In an igniting apparatus, the combination of a perforated holder for the ignitable compound, one or more movable igniters arranged to strike upwardly from below the holder, and mechanism for operating said igniters, substantially as described.

15 2. In an igniting apparatus, the combination of the trough or holder provided with the through-slot or perforations in the bottom thereof, the upwardly-striking igniters 10, arranged below the holder, and mechanism for operating said igniters, substantially as described.

25 3. In an igniting apparatus, the combination of the holder provided with the through-slot or perforations in the bottom thereof, the upwardly-striking igniters pivoted below and to one side of the holder, and mechanism for operating said igniters, substantially as described.

30 4. In an igniting apparatus, the combination of the perforated holder for the compound, the igniter 10, an air-engine, the shaft 12, the pulley 24 on said shaft, the ligament connecting said pulley with the rod of the

air-engine, the spring 15, and connections between said shaft and said igniter, substantially as described.

35 5. In an igniting apparatus, the combination of the perforated holder for the compound, the igniter 10, an air-engine for operating said igniter, and mechanism having an adjustable member for connecting said engine and said igniter 10, substantially as described.

40 6. In an igniting apparatus, the combination of the perforated holder for the compound, the pivoted upwardly-striking igniter, an air-engine and connections for causing the igniter to strike upwardly, and a retracting-spring for the igniter, substantially as described.

45 7. In an igniting apparatus, the combination of the foraminous holder for the compound, the rock-shaft 12 below and to one side of the holder, the igniters carried by said shaft and arranged to move through more than ninety degrees, an air-engine and connections for moving the igniters upwardly, and a retracting-spring, substantially as described.

50 Signed at New York city, in the county of New York and State of New York, this 18th day of December, A. D. 1896.
